ELECTROMAGNETIC RELAY

Norman F. Agnew, Wilkinsburg, Pa., assignor to
The Union Switch & Signal Company, Swiss-
vale, Pa., a corporation of Pennsylvania

Application September 19, 1939, Serial No. 295,619

2 Claims. (Cl. 175—336)

My invention relates to electromagnetic relays, and has particular reference to means for regulating or compensating electromagnetic relays for variations in ambient temperature.

An object of my invention is the provision of electromagnetic relays having improved operating characteristics under varying conditions of ambient temperature.

Another object of my invention is the provision of electromagnetic relays incorporating novel and improved means for compensating the voltage characteristics of such relays for ambient temperature in such manner as to provide relays having inverse voltage characteristics.

A further object of my invention is the provision of electromagnetic relays incorporating novel and improved means for varying the magnitude of the tractive force required to operate the relays in accordance with variations in the ambient temperature.

Another object of my invention is the provision, in an electromagnetic relay, of novel and improved means for varying an air gap in the relay magnetic circuit in accordance with variations in ambient temperature in such manner as to provide inverse straight line operating characteristics for the relay over a wide range of ambient temperature.

Other objects and advantages of my invention will appear from the following description.

I shall describe one form of apparatus embodying my invention, and shall then point out the novel features thereof in claims.

In the accompanying drawing, Fig. 1 is a graph in which curve *a* illustrates the manner that the voltage characteristics of an uncompensated relay are affected by variations in ambient temperature. Curves *b* and *c* illustrate, respectively, the voltage characteristics of a partially compensated relay and a relay compensated in accordance with my invention. Fig. 2 is a diagrammatic view of a preferred form of electromagnetic relay embodying my invention.

Referring first to curve *a* of Fig. 1, which illustrates the voltage characteristics of an uncompensated electromagnetic relay, it is evident from an inspection of this curve that the applied voltage at which an uncompensated relay picks up is directly proportional to the ambient temperature. This is due to the fact that the copper winding ordinarily employed in a relay has a positive temperature coefficient, so that an increase in ambient temperature causes a corresponding increase in resistance of the winding with the result that for a constant applied volt-

age, the current flow decreases. In order, therefore, to obtain the tractive force necessary to operate the relay armature, the voltage applied to the relay must be increased as the ambient temperature increases.

At times, however, it is desirable to employ a relay which picks up at a higher voltage at low temperatures than it does at high temperatures, or in other words, a relay having the characteristics of inversely varying its pick-up voltage with ambient temperature variations. This type of relay is particularly suitable for use in two-rate battery charging systems, such, for example, as illustrated in United States Letters Patent No. 1,885,908, granted to R. M. Gilson on November 1, 1932, since it is a well recognized fact that the terminal voltage of storage batteries varies inversely with ambient temperatures.

It is known that a particularly effective means 20 for compensating relays for ambient temperature is to vary the length of an air gap interposed in the relay magnetic circuit in accordance with ambient temperature variations. Heretofore, ambient temperature compensation 25 has been obtained by utilizing the linear deflection of a thermally responsive element to produce corresponding linear variations in the length of the armature air gap. This method provides only partial compensation for ambient temperature, as can be seen from the fact that the tractive force exerted by an electromagnet on its armature varies inversely as the square of the length of the armature air gap, the force being represented by the formula

$$F = S \left(\frac{NI}{l_c} \right)^2$$

where

F = force in pounds

S = cross-sectional area of core in square inches

N = number of turns of winding

I = current in amperes

l = length of air gap in inches

c = a constant

45 The voltage characteristics of a typical relay compensated in the above manner is illustrated in curve *b* of Fig. 1, from which curve it can be seen that the pick-up voltage of the relay remains substantially constant throughout the lower half of the temperature range but drops sharply in the upper half of the range.

In order, therefore, to provide a relay having inverse straight line operating characteristics 50 over a wide range of ambient temperature, I pro-

pose to improve the control established by the linear deflections of a thermally responsive element over an air gap interposed in the relay magnetic circuit. Referring now to Fig. 2, the reference character R designates a relay embodying my invention. As shown, relay R comprises a U-shape frame 5 having a magnetizable core 6 connected thereto in a suitable manner, as by means of a screw 7. Mounted on core 6 is a magnetizing winding 8, which ordinarily is constructed of copper wire and which possesses a positive temperature coefficient of resistance. An armature 9 provided for the electromagnetic relay is pivotally mounted at 10 and normally occupies a retracted position by virtue of the weight and spring force of a contact member 12 which is operatively connected with armature 9. As shown, contact member 12 engages another contact member 11 to form a circuit controlling contact 13-14, which contact is opened whenever winding 8 is energized sufficiently to attract armature 9 to its attracted position.

Relay R further comprises a thermally responsive element 15 here shown in the form of a bimetallic strip formed of two metals having different coefficients of thermal expansion. The thermally responsive element is incorporated into relay R by rigidly securing one of its ends and positioning the other or free end of the element in such manner as to engage armature 9 to limit the movement of the armature to its retracted position. The element 15 is arranged to deflect downwardly from its illustrated position as the temperature increases and to deflect upwardly as the temperature decreases. It is readily apparent that as the free end of element 15 deflects due to variations in ambient temperature, the position at which element 15 engages armature 9 is altered due to the deflection in the element to thereby vary the length of the air gap between the pole piece of core 6 and armature 9, and as a result the tractive force required to operate the armature to its attracted position is varied.

Relay R additionally includes suitable means for modifying the control established by thermally responsive element 15 over the armature air gap. As here shown, such modifying means comprises a cam 16 formed on the rear face of armature 9 and disposed to be engaged by the free end of the thermally responsive element. The shape of cam 16 is so designed with respect to the deflection of element 15 due to ambient temperature variations that the free end of the element engages the surface of cam 16 to permit a predetermined amount of movement of the armature toward or away from core 6 in accordance with the predetermined decrease or increase in ambient temperature.

It follows that by properly proportioning cam 16 and thermally responsive element 15, any desired voltage characteristic can be provided for relay R. Thus, for example, the surface of cam 16 can be so selected that the armature opening of relay R is varied in such manner that the relay will pick up at a constant voltage regardless of variations in ambient temperature, or, by changing the surface of cam 16, the relay can be designed to have a straight line pick-up voltage characteristic inversely proportional to ambient temperature, similar for example, to curve c of Fig. 1.

An advantage of a relay embodying my invention is that uniform regulation is obtained over a wide range of ambient temperature, thus permitting the construction of relays having straight line voltage characteristics substantially similar to the voltage characteristics of storage batteries, and providing a relay having improved voltage characteristics suitable for use in two-rate battery charging systems.

Although I have herein shown and described only one form of electromagnetic relay embodying my invention, it is understood that various changes and modifications may be made therein within the scope of the appended claims without departing from the spirit and scope of my invention.

Having thus described my invention, what I claim is:

1. A relay comprising, in combination, an electromagnet, a pivoted armature mounted for movement relative to said electromagnet and biased therefrom, a thermally responsive element having a surface which moves with temperature changes transversely to the line of motion of said armature, and a cam surface formed on said armature and cooperating with said moving surface of said thermally responsive element for limiting the movement of said armature relative to said electromagnet, said cam surface being shaped throughout to provide said relay with a linear temperature-voltage characteristic throughout a relatively wide range of ambient temperatures.

2. A relay comprising an electromagnet and an armature mounted for movement relative to said electromagnet and biased therefrom, a cam provided on said armature and a thermostatic element having a surface which moves with temperature changes transversely to the line of motion of said armature, said cam having a surface engageable by said surface of said thermostatic element and shaped throughout to cooperate with said surface of said thermostatic element to provide said relay with linear temperature-voltage characteristics.

NORMAN F. AGNEW.
